UNITED STATES PATENT OFFICE.

WILLIAM LOUDEN, OF FAIRFIELD, IOWA.

MANGER FOR ANIMAL PENS AND STALLS.

1,297,974.

Specification of Letters Patent Patented Mar. 18, 1919.

Application filed January 2, 1914, Serial No. 809,907. Renewed February 8, 1919. Serial No. 275,852.

To all whom it may concern:

Be it known that I, WILLIAM LOUDEN, a citizen of the United States, residing at Fairfield, in the county of Jefferson and State of Iowa, have invented a new and useful Improvement in Mangers for Animal Pens and Stalls, of which the following is a specification.

My invention relates to mangers mainly 10 designed for calf pens although adapted for other uses such as cow stalls and the like, and it consists of an improvement whereby the manger will be more readily lifted and held in elevated position for cleaning and 15 other purposes. Also of other features set forth in this specification and more definitely defined in the claims.

In the accompanying drawings forming part of this specification, Figure 1 is a perspective of a portion of a calf pen embodying my invention. Fig. 2 is the same showing the manger in elevated position. Figs. 3 and 5 are enlarged detail views which will be hereinafter explained. Fig. 4 is a transverse section on line 4-4 of Fig. 3, said line being diverged at one end to form two lines on different planes. Fig. 6 is a transverse section on line 6-6 of Fig. 5. Fig. 7 is an enlarged side view to be hereafter explained. Fig. 8 is a horizontal section on line 8-8 of Fig. 7. Fig. 9 is a transverse section on line 9-9 of Fig. 1. Fig. 10 is an enlarged detail view.

Referring to the drawings, A represents 35 the top rails and B, the upright posts of a calf pen which may be connected directly to the floor of the building in which the pen is located, or be attached to the curb C or to a lower rail D as shown in the drawings. 40 One side of the pen is usually provided with stanchion members E which are hinged at their lower ends and may be opened and closed by means of a shift-rod F and operated by a lever G. A manger consisting of 45 a back H and partitions I is attached to the side of the pen or stall where the animals are fed by means of hinges J connected to the adjacent posts B, whereby the manger may be raised from the feeding position shown in Fig. 1 to the cleaning position shown in Fig. 2.

The hinges J have their ends set at substantially right angles to each other and when the manger is in lowered position the 55 lower ends of the hinges, which will be horizontally disposed, are attached to the

manger partitions by bolts *a* the heads of which are preferably countersunk on one side of the partition. The other end of the hinges, which will be vertically disposed, 60 are fitted with eyes which are pivoted to castings K which in turn are clamped to the post B by bolts *b* which pass through the pivot casting and also through another casting L on the other side of the post, the inner 65 faces of the castings K and L being preferably concave to fit the contour of the post.

The end of the castings L next the manger is extended out to support the lower ends of stationary shields M which are used to secure a more effective separation between the compartments of the manger and are attached to each of the posts B immediately above the partitions. The upper ends of the shields are secured to the posts B by clamps 75 N held together by bolts *d* and their lower ends are connected to the extended ends of the castings L, preferably by rivets *e*, the heads of which on the side of the shields next the partitions I are countersunk so that 80 there will be no projecting parts to catch on the partitions when the latter are in elevated position. Fig. 3 is an enlarged side view of the upper inner corner of one of the partitions I and the lower inner corner of one 85 of the stationary shields M, and also of one of the irons which connect them to the posts B.

As will be seen by Fig. 2, the partitions I will telescope with or slide up by the stationary shields M when the manger is raised, and in order to prevent them from getting sprung apart and to steady the position of the outer lower corners of the shields, I affix keepers O to the outer upper edges of 90 the partitions I. These keepers are provided with fingers to catch over the outer edge of the shields and hold them in operative position with the partitions. The outer edges of the shields are cut on a radius to 95 correspond with the pivot of the hinge J whereby the finger of the keepers O will slide up and down on the edge of the shields from bottom to top. The keepers O are preferably secured to the partitions I by 100 rivets *g*.

To assist in raising the manger and to hold it in elevated position when raised, one end of a coiled tension spring S is connected to one or more of the hinges J while 110 the other end of the spring is connected by means of a holder R to the upper end of the

post B to which the hinge is pivoted, as shown by Fig. 5. The holder is preferably made of two parts which are clamped upon the post by bolts *h*. The end of the holder 5 to which the spring is connected is preferably bent downward or made depending with mating thimbles or ferrules *r* through which a bolt *i* is passed and above which there is an opening between the sides of the 10 holder to admit an eye on the upper end of the spring.

About midway and near the center of the angle in the hinge *J* is an eye *Q* in which one end of a hook or link *T* is inserted. The 15 hook *T* is preferably double ended and the other end is hooked into an eye in the lower end of the spring *S*. The tension of the spring is adjusted by slightly loosening the bolts *h* in the holder *R* and driving it up on 20 the post *B* with a hammer or otherwise. The best way is to raise the manger as high as it will go and prop or tie it in this position. Then drive up the holder *R* until the spring 25 will hold the manger in elevated position.

The spring being connected to the hinge near the center of its angle, its leverage on the hinge will be greatest when the tension 30 of the spring is weakest and vice versa. The friction of the partitions *I* on the shields *M* which is assured and may to some extent be 35 regulated by the keeper *O*, will also assist the springs in holding the manger in elevated position. The combination of the pivot casting *K* for the manger hinge *J* with the lower support casting of the shield *M* also contributes to the certainty of this result and 40 simplifies the construction.

The entire arrangement is simple and effective in operation and the manger with the 45 springs and shields may be used with any kind of an animal pen or with cow stalls, as well as calf pens. If preferred four or five compartments may be made in the manger instead of three as shown in Figs. 1 and 2, in which case additional springs should be 50 used. When the pen is long the manger may be divided into sections of three to five compartments each with springs in proportion to the length of the manger.

50. What I claim is—

1. In animal pens and stalls having a series of upright posts, a manger having a series of partitions dividing it into compartments, a series of hinges having one of their 55 ends bent upwardly at substantially right angles to the other, said upper ends being pivoted to an adjacent post and the other being attached to the inner end of one of the partitions, a holder consisting of a clamp 60 adjustably connected to the upper end of the post, a vertically disposed tension spring having its upper end connected to the holder and its lower end connected to the angular center of the hinge.

65. 2. In animal pens and stalls having a

series of upright posts, and a manger hinged thereto, angular shaped hinged pieces having attaching eyes approximately in their angular centers, secured at one end to the upper edge of the manger, the other ends of 70 the hinged pieces being pivoted to adjacent posts, tension-springs having their lower ends connected to the attaching eyes of the hinged pieces, and their upper ends connected to the upper ends of the posts, and holders 75 made in two parts adjustably bolted to the posts as a means for connecting the springs under proper tension to said posts.

3. In animal pens and stalls having a series of upright posts, a manger having a 80 series of partitions hinged to the posts and dividing the manger into compartments, stationary shields attached to the posts above the partitions, by which the partitions will pass when raised, and keepers adapted to 85 slide over and support the outer edges of the shields, secured to the outer edges of the partitions.

4. In animal pens and stalls having a series of upright posts, a manger having a series 90 of partitions hinged to the posts and dividing the manger into compartments, stationary shields having their upper ends secured to the upper ends of the posts by clamps and their lower ends secured by castings, one 95 side of which forms pivots for the hinges of the manger.

5. In animal pens and stalls having a series of upright posts, a manger having a series 100 of partitions hinged to the posts and dividing the manger into compartments, stationary shields having their upper ends secured to the upper ends of the posts by clamps and their lower ends secured by castings, one side 105 of which forms pivots for the hinges of the manger and the adjacent sides of the partitions and shields being disposed closely together and made smooth so they will freely pass by each other.

6. In animal pens and stalls having a series 110 of upright posts, a manger having a series of partitions dividing it into compartments, a series of hinge members having their ends set at substantially right angles to each other and having attaching eyes approximately in 115 their angular centers, one of the sets of ends of said hinge members being connected to the manger partitions and the other ends pivoted to some of the upright posts at points above the attaching eyes of the hinge members 120 when in lowered position, holders secured to said posts above the pivots, and tensioned springs placed along side and approximately parallel with said posts, the upper ends of the springs being attached to 125 said holders and their lower ends being connected to the eyes in the hinge members.

7. In animal pens and stalls having a series of posts, a manger having ends made of 130 slidably-connected members, castings se-

cured in pairs to certain of said posts, one casting secured to one member of the manger end to rigidly secure it in place, and the other casting of the pair forming a pivot, 5 and a hinge secured to the other member of the end of the manger and mounted to turn on said pivot.

8. In animal pens and stalls having a series of posts, a manger having ends made of 10 slidably-connected members, castings secured in pairs to certain of said posts, one casting secured to one member of the manger

end to rigidly secure it in place, and the other casting of the pair forming a pivot, a hinge secured to the other member of the 15 end of the manger and mounted to turn on said pivot, and keepers secured to one of said members and slidably embracing the edge of the other.

Fairfield, Iowa, Dec. 31, 1913.

WILLIAM LOUDEN.
